Primary Examiner — Karen S Acker*Assistant Examiner* — Elizabeth S Ko(74) *Attorney, Agent, or Firm* — Dinsmore & Shohl LLP(57) **CLAIM**

The ornamental design for a connector for tubular sections, as shown and described.

DESCRIPTION

FIG. 1 is a perspective view of a connector for tubular sections;

FIG. 2 is a front view of FIG. 1;

FIG. 3 is a rear view of FIG. 1;

FIG. 4 is a right side view of FIG. 1;

FIG. 5 is a left side view of FIG. 1;

FIG. 6 is a top view of FIG. 1; and,

FIG. 7 is a bottom view of FIG. 1.

The broken lines in the drawings depict portions of the connector for tubular sections that form no part of the claimed design.
